KNOCKDOWN HIGH CHAIR

John L. Ohman, Gardner, Mass., assignor to
 Marlboro Mfg. Co., Inc., Marlboro, N. H., a corporation of New Hampshire

Application January 18, 1952, Serial No. 267,059

5 Claims. (Cl. 155—196)

1

This invention relates to improvements in high chairs and the like. More particularly it provides a high chair which may be packaged for storage and shipment in a partially assembled condition, and which quickly and easily may be completely assembled by any purchaser who follows a few simple directions.

Conventional high chairs, because of their spread and height, are awkward units to package or crate and require considerable space when even a relatively small number of them are to be stored by a jobber or retailer, or are to be shipped to any particular destination. Freight charges for transportation of high chairs have excessively increased the cost of such chairs to the user, particularly in those cases where the ultimate user-purchaser has been located a considerable distance from the place of manufacture of the chairs.

It is among the objects of the present invention to provide a high chair which may be manufactured in a few permanently assembled generally flat sections and a few connecting elements, all of which may be packaged in a carton having dimensions of the order of thirty inches by twenty inches by four inches, and which quickly and simply may be completely assembled by anyone who follows a few simple directions involving the use of only a wrench which is provided in the carton. According to the invention, a chair back section and two side sections are permanently assembled, with each side section comprising two legs and one arm of the chair. A seat, a foot rest, and two leg braces are separately provided, and threaded projections on particular parts are readily insertible in holes in other parts to easily and quickly assemble the parts in loose proper relationships, following which applying and tightening of a nut on each threaded projection produces an extremely rigid and stable high chair on whose arms a tray may be adjustably mounted in a conventional manner.

Another object of the invention is to provide a knock-down high chair having generally flat permanently assembled sections and a plurality of separate connecting elements, which sections and elements may be packaged compactly in a relatively small carton, for shipment and storage, and readily and quickly may be set up into a rigid completely assembled high chair by applying and tightening nuts on threaded projections permanently fixed on the sections and elements and angularly disposed for ensuring proper inclinations of the chair back and legs in the assembled high chair.

2

It is, moreover, my purpose and object generally to improve the structure of high chairs and the like and more particularly to provide a knock-down high chair which is easily and quickly convertible between its knocked-down and its fully assembled conditions.

In the accompanying drawings:

Fig. 1 is a front elevation of a completely assembled high chair embodying features of the invention;

Fig. 2 is a side elevation of the completely assembled high chair of Fig. 1;

Fig. 3 is a top plan view of the assembled chair of Figs. 1 and 2;

Fig. 4 is a detail cross-sectional view on line 4—4 of Fig. 1, on a larger scale;

Fig. 5 shows the various sections and elements of the high chair in separated relationships;

Fig. 6 represents a flat rectangular carton in which the knocked-down chair may be packaged for shipment and storage; and

Fig. 7 is an edge elevation of a modified form of side section each of whose legs is in two parts hinged together, the upper part of the side section being folded over upon the lower part thereof.

Referring to the drawings, and more particularly to Fig. 5 thereof, the high chair comprises two similar side sections indicated generally at 10 and 12, each having two legs 14, 16 permanently secured together in inclined relation by a chair arm 18, which is rigidly secured to the upper ends of the legs, and by a brace bar or rung 20 which extends between and is rigidly connected to the legs at a location substantially spaced from the lower ends of the legs. Each leg 14, 16 has two holes 22, 24 drilled therethrough at predetermined spaced locations along each leg, and each leg 14 has another hole 26 drilled therethrough between and transversely of the direction of extent of the holes 22, 24. One end of each chair arm 18 preferably is rounded at 18' for constituting the forward end of the arm, and the rear end of each arm has a threaded projection 28 rigidly secured thereto and projecting from the end of the arm at a predetermined inclination to the plane of extent of the arm. Each arm additionally is provided with a perforated metal strip 30 at that side of the arm which is outermost in the assembled chair.

A chair seat is represented at 32 and has two threaded projections 34 rigidly secured to each of its opposite side edges and projecting from these edges at a predetermined inclination to the plane of the seat. The seat projections 34 at one side edge of the seat are adapted to be

inserted through the holes 22 in the legs of one side section 10 of the chair and the similar projections 34 at the other side edge of the seat are adapted to be inserted through the holes 22 in the legs of the other side section 12 of the chair. The side edges of seat 32 preferably are slightly rounded as shown in Fig. 5, and the holes 22 through the legs 14, 16 are drilled perpendicular to the outer surface of each leg. Hence, when the threaded projections 34 are inserted through the leg holes 22, their said inclination to the plane of the seat is such that they extend through holes 22 and extend somewhat beyond the legs in perpendicularity to the outer surfaces of the legs when the legs are inclined relative to each other as shown in Fig. 1. The slight rounding of the seat edges facilitates the attainment of a good bearing contact between the seat edges and the inclined legs when these elements are drawn together and effectively secured, as later will be described.

The rear edge of seat 32 is also slightly rounded and has two threaded projections 36 rigidly secured thereto and projecting therefrom at a predetermined inclination to the plane of the seat, the inclination of these projections 36 being opposite to the inclination of the side edge projections 34.

A chair back section is indicated generally at 38 and comprises the two relatively inclined posts 40 which are rigidly and permanently connected together at their upper ends by the transverse member 42. A panel member 44 is permanently connected to the posts 40 and to member 42.

Each post 40 of chair back section 38 has two holes 46, 48 drilled therethrough, the holes 46 being at the lower ends of the posts for reception of the threaded projections 36 at the rear edge of seat 32, and the holes 48 being located for reception of the threaded projections 28 at the rear ends of the chair arms 18 when the chair is being assembled. The holes 46, 48 preferably are perpendicular to the rear surfaces of posts 40, and the inclinations of the projections 28 and 36 are such that the projections extend through the holes 46, 48 and project beyond the posts 40 in perpendicularity to the rear surfaces of the posts when the chair back section is inclined relative to the chair seat and chair arms as shown in Fig. 2.

Two similar leg braces or rungs are represented at 52, 54, the opposite ends of each having a threaded projection 56 rigidly secured thereto and projecting therefrom at a predetermined inclination to the brace or rung. The projection 56 at one end of brace 52 is adapted to be inserted in the hole 24 in one of the rear legs 16 of the chair and the projection 56 at the other end of brace 52 is adapted to be inserted in the hole 24 in the other rear leg 16. Similarly, the projections 56 on brace 54 are adapted to be inserted in the holes 24 in the two front legs 14 of the chair. Ordinarily these braces 52, 54 should be assembled loosely between the chair legs following insertion of the seat projections 34 in the holes 22 of the legs so that the lower ends of the legs may be spread sufficiently for insertion of the brace projections 56 in the lower leg holes 24, after which the side sections may be pressed toward each other against the opposite side edges of the seat and against the opposite ends of the braces 52, 54, and be secured in place by screwing a nut 58 on the projecting end of each threaded pro-

jection 34 and 56, preferably with a washer 60 intervening between each nut and the adjacent leg surface. The chair back section 38 then may be mounted on the threaded projections 28 and 36 of the chair arms and seat, and be secured by nuts 58 screwed on the projections.

A foot rest 62 has the two threaded projections 64 rigid thereon and adapted to be inserted in the holes 26 in the front legs of the chair, 10 and to be secured in place across the front legs by nuts 58.

The chair is now completely assembled excepting the tray 66 which may be adjustably and removably mounted on the chair arms 18 in 15 a conventional manner. As shown, each end of the tray has a spring biased plunger 68 mounted on a depending bracket 70 and the inner ends of the plungers are adapted to engage selectively in the perforations in the strip elements 30 on the outer sides of arms 18. The plungers 68 may be manually drawn outward to release the tray for adjustment along the chair arm or for removal from the chair.

It will be obvious, from the foregoing description, 25 that my improved high chair as represented in Figs. 1-5, in knocked-down condition, may be compactly packaged in a generally flat rectangular carton, or other container, of the general shape shown in full lines in Fig. 6, for shipment and storage with substantial savings in space and shipping and storage costs. Yet the sections and elements of the chair are so constructed that they can be quickly assembled into a rigid and stable high chair by anyone with 30 ordinary intelligence who follows a few simple instructions. The parts go together readily and may be rigidly secured by merely applying and tightening a few nuts with a wrench which may be included with the nuts and washers in an 35 envelope accompanying the chair parts.

My improved high chair may be made still more compact, in knocked-down condition, by making each leg of the chair in two parts hinged together at 72 (Fig. 7) so that each side section 45 10, 12 may be folded upon itself, as in Fig. 7, for packaging. When the side sections 10, 12 are folded, as suggested in Fig. 7, the knocked-down high chair may be packaged in a carton of the relative size indicated by dotted lines in Fig. 6, 50 its dimensions being 20" x 16" x 8", for example, which is well within the latest Postal Regulations governing the permissible size of parcel post packages. The legs of this high chair become rigid when the chair is assembled in the manner 55 earlier described herein, the connections between the legs and the chair seat 32 above the hinges 72 coating with the foot rest 62 and brace bars 52, 54 below the hinges to maintain the chair legs rigid.

60 It is intended that the patent shall cover, by suitable expression in the appended claims, whatever features of patentable novelty exist in the invention disclosed.

I claim as my invention:

65 1. A high chair comprising two side sections, each having two legs and one arm rigidly and permanently connected together with the arm at the upper end of the legs and with the legs extending in a common plane from the arm and having relative inclination in said common plane with greater spread at their lower ends than at their upper ends, a brace element rigidly and 70 permanently maintaining the said spread of the lower ends of the legs of each said side section, there being two spaced holes through each leg

of each said side section extending transversely of said common plane of the legs of each side section, one said hole in each leg being at one predetermined location below the said arms, and the other said hole in each leg being at another predetermined location closer to the lower end of each leg, a seat element having a pair of threaded projections at each of its opposite side edges, each adapted to extend through the upper hole in a different one of said legs and to project beyond the legs, two similar brace elements, each having a threaded projection at each of its ends, the said projections on one brace element being adapted to extend through the lower ones of said holes in one leg of each said side section and to project beyond the legs, and the said projections on the other brace element being adapted to extend through the lower ones of said holes in the other leg of each said side section and to project beyond the legs, a chair-back section comprising two posts and means extending between the posts permanently securing the posts in a predetermined spaced relation, each said post having two spaced holes therethrough of which one hole of each post is adapted to receive a said threaded projection on the rear end of one of the chair arms with said projections extending through and beyond the posts, two threaded projections fixed on the rear edge of said seat element, each adapted to extend through the other said hole in different ones of the chair-back posts and to project beyond the posts, and a nut screwed on each said threaded projection and securing said sections and elements rigidly together.

2. A high chair comprising two similar side sections, a chair-back section, and a seat element detachably secured together, each said side section having two legs permanently connected together by a chair-arm at one end of the legs with the legs inclined relative to each other in a common plane, and each leg of each side section having a hole therethrough perpendicular to said plane at a predetermined location spaced from the chair-arm, said chair-back section having two posts with connecting means rigidly and permanently connecting the posts in spaced relation in a common plane, each said post having two holes therethrough perpendicular to said common plane of the posts at predetermined spaced locations along the posts, two threaded projections fixed to each of two opposite side edges of said seat element, the said projections at one side of the seat element extending respectively through the holes in the legs of said side section and the said projections at the other side edge of the seat element extending respectively through the holes in the legs of the other said side section, two threaded projections rigid on the rear edge of said seat element extending respectively through the lower hole in said chair-back posts, a single threaded projection rigid on the rear end of each said chair-arm and extending each through the upper hole in one of said chair-back posts, and a nut screwed on the end of each said threaded projection securing said side sections, chair-back section and seat element in rigid assembled condition.

3. In a high chair having two similar side sections, each comprising two legs and one arm rigidly and permanently secured together with the arm connecting the upper ends of the legs, the combination therewith of a seat element removably supported on and between said side sections, said seat element having two threaded projections rigid on each of two opposite side edges of

the seat element and projecting therefrom at a predetermined inclination to the plane of the seat element, the two legs of each said side section being in a common plane and the said common plane of the legs of one side section being inclined with respect to the said common plane of the legs of the other side section, each leg of each side section having a hole therethrough at a predetermined location therealong and perpendicular to the said common plane of the leg, and a different one of said seat projections extending through a said hole in each leg, a nut screwed on each of said projections clamping the legs against said opposite side edges of the seat element, and rigid means at the back of the chair detachably secured to the rear edge of said seat element and to the rear end of each of said arms of said side sections.

4. In a knock-down high chair having leg and arm elements permanently and rigidly connected together to provide two similar side sections, and having a back section and a seat element, means for detachably connecting together said side sections, back section and seat element with the seat element supported on and between said side sections, said means comprising two threaded projections rigid on each of two opposite side edges and on the rear edge of said seat element, a single threaded projection rigid on the rear end of each of said arm elements, there being a hole through each of said leg elements and a different one of said side edge seat projections being inserted through said hole in each leg element, there being four holes through said back section and said rear edge seat projections being inserted one in each of two of said holes in the back section, said arm projections being inserted one in each of the other two holes in the back section, and a nut screwed on the end of each said projection rigidly but detachably securing said side and back sections and said seat element together.

5. In a knock-down high chair having leg and arm elements permanently connected together to provide two similar side sections, and having a back section and a seat element, each leg of each said side section being in two parts hinged together at a location spaced a substantial distance from each end of the leg whereby the upper portion of each said side section may be folded over upon the lower portion thereof when the knocked down chair is to be packaged, means for detachably connecting together said side sections, back section and seat element after the hinged legs of the side sections have been opened to their full lengths, the seat element being supported on and between said side sections, said connecting means comprising two threaded projections rigid on each of two opposite side edges and on the rear edge of said seat element, a single threaded projection rigid on the rear end of each of said arm elements, there being a hole through each of said leg elements and a different one of said side edge seat projections being inserted through said hole in each leg element, there being four holes through said back section and said rear edge seat projections being inserted one in each of two of said holes in the back section, said arm projections being inserted one in each of the other two holes in the back section, and a nut screwed on the end of each said projection rigidly but detachably securing said side and back sections and said seat element together, said seat element being connected to the side sections above the said leg hinges, and means below the

2,675,066

7

leg hinges rigidly connecting the said side sections together.
